CLAIM

The ornamental design for a smart watch, as shown and described.

DESCRIPTION

FIG. 1 is a front and top perspective view of a smart watch, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view thereof, taken from encircled portion 9 in FIG. 1; and,

FIG. 10 is an enlarged view thereof, taken from encircled portion 10 in FIG. 2.

The evenly spaced broken lines in the figures illustrate portions of the smart watch that form no part of the claimed design. The dash dot dash broken lines in FIGS. 1, 2, 9 and 10 are included to show partially enlarged views only and form no part of the claimed design.
